UNITED STATES PATENT OFFICE.

GUSTAVE A. WILKE, OF MILWAUKEE, WISCONSIN.

CARD PACKAGE.

Application filed June 11, 1924. Serial No. 719,371.

To all whom it may concern:

Be it known that I, GUSTAVE A. WILKE, a citizen of the United States, residing at Milwaukee, county of Milwaukee, and State of Wisconsin, have invented new and useful Improvements in Card Packages, of which the following is a specification.

This invention relates to improvements in card packages. More particularly stated, 10 this invention relates to a novel and improved combination of detachable business or calling cards with a case or container to comprise a package therewith.

It is the primary object of this invention 15 to provide a successfully operative package of cards and attached stub in loose leaf form, provision being made for carrying the stubs with such security and rigidity, and for so furthering the detachment of the cards 20 therefrom as to make it practical to use the loose leaf system in a package of this character.

Where detachable cards have heretofore 25 been used, their stubs have commonly been bound together in book form by means of staples or the like, and the arrangement has been such that it was necessary to remove wholly each such book from the carrying case or container before a new book could be 30 inserted therein. This was the logical consequence of the fact that the stubs were bound together unitarily and could only be inserted or removed as a unit. Persons desiring to make a series of calls and finding 35 that their book or case contained but few business cards were obliged either to carry a separate filler with them or else to throw away the old filler with the remaining cards and to insert a complete new filler in their 40 container. It is much more economical merely to remove from the package or from the container those stubs from which cards have been detached and to replace them with a series of new stubs and attached cards. 45 The difficulty heretofore has been both in the provision of an adequately secure and rigid mounting for the stubs and also in the provision of a card which could be detached from its stub with sufficient ease. 50 Obviously, the rigidity of the mounting and the ease with which the card may be detached will be determinative of the success of any device involving the loose leaf principle.

In the drawings:

Figure 1 is a view in perspective of a device embodying this invention.

Figure 2 is an enlarged detail taken in section on the line indicated at 2-2 in Figure 1.

Figure 3 is an enlarged detail of a portion of a single card and the stub thereof, the card being partially detached from its stub.

Like parts are identified by the same reference characters throughout the several views.

The particular form of the case or container 5 is broadly immaterial to this invention. The container illustrated includes a 70 pliable leather back 6 to which a flap 7 is stitched in a manner to comprise a pocket in which loose cards, such as those received from others, may be preserved. Preferably integrally connected with the back 6 is a flap 75 8 which extends upwardly therefrom and over the stubs of the cards, hereinafter to be described, such flap being adapted to protect and conceal the stubs and also to carry the stub positioning means which forms an 80 important part of this invention. A plurality of spaced posts, one of which is shown in the section in Figure 2 at 10, are mounted in the flexible backing 6 and project upwardly 85 therefrom. These posts are headed at 11 to receive the glove fasteners of flap 8.

Each card 15 is formed integrally to provide a stub portion 16. Each card is preferably scored both from above and beneath, as indicated at 17 and 18 respectively, to define a line upon which the cards may readily be separated from their respective stub portions. The lines of scoring 17 and 18 will preferably be vertically superimposed and will so nearly meet each other as to leave a very thin web of material connecting the card with the stub. I am fully aware that double scored detachable cards have hitherto been patented, but I do not claim this feature independently of other features referred to above and hereinafter to be more fully described. In the ordinary card package double scoring is not important since, where the stubs are stapled or otherwise bound in book form, such stubs may be held with sufficient security so that single scored cards can be detached with sufficient ease for practical purposes.

Each of the stub portions 16 of the several cards is provided with spaced apertures 19 adapted to receive the posts 10. These apertures are preferably of exactly the cross sectional diameter of the posts so that they may be mounted on the posts with a close fit. It has been found that such posts as that illustrated at 10 will hold the stubs with adequate rigidity to permit of the clean-cut separation therefrom of double scored cards, thus making it possible to put up a card package on the loose leaf principle. It follows that any user of this device may at any time remove from the posts 10 those stubs from which the cards have already been detached and may replace the old stubs with new card and stub units to any desired number to fill his container. It has also been found that if the container is at all times kept full of stubs the rigidity with which the stubs are held will be increased.

I claim:

1. In a device of the character described, a unit comprising separable card and stub elements, said unit being scored above and below along the desired line of separation between said elements, and said stub element being provided with spaced apertures adapted to receive positioning posts.
2. In a card package, the combination of a plurality of individual calling cards and attached stubs formed integrally with respective cards and separable therefrom, the boundary between each card and its respective stub being defined by continuous straight scoring or cutting adapted to permit the card to be torn from the stub with a clean-cut margin and the remaining boundaries of each card being free, all of said stubs being provided with laterally spaced aligned openings adapted to receive mounting posts, whereby to secure said stubs pending the separation of cards therefrom.
3. In a card package, the combination of a series of separable units each including apertured stub portions and card portions separable therefrom, said units being scored from above and below to define a line of separation between said portions, and releasable positioning means extending through the apertures of said stub portions and adapted independently to fix each of such stub portions against displacement, whereby to facilitate the separation of said card portions therefrom.
4. In a card package, the combination of

a series of superimposed independent units of calling card weight each provided with continuous straight and superimposed score lines across its upper and under surfaces whereby to divide each unit into a stub portion and a single readily detachable card portion adapted for use as a calling or business card, said stub portions being provided with aligned apertures adapted to receive mounting posts for the independent positioning of said units, said superimposed score lines being adapted to facilitate the ready separation with clean straight margins of individual card portions from their respective stub portions held only at such posts.

5. In a device of the character described, the combination with a flexible back and a pair of spaced posts projecting therefrom, of a flap connected with said back and provided with glove fasteners engageable with the tops of said posts, and a series of card and stub units each provided with apertures in its stub portion engaged upon said posts, whereby to fix each stub portion in position independently of the stub portions of other units and each of said units being double scored from above and below, whereby to facilitate the separation of cards from the stub portions of units so positioned.

6. In a device of the character described, the combination with a backing member and a pair of spaced posts, of fastening means detachably engageable with said posts, and a single series of superimposed cardboard units of calling card weight including separable calling card and stub portions and each provided with apertures in its stub portion receiving and detachably engaged upon said posts and removably retained thereon by said means, whereby to fix each stub portion in position independently of the stub portions of other units, each of said units being scored from above and below in continuous superimposed straight lines, whereby the card portion of each unit is readily detachable to leave a smooth straight edge provided by said score lines despite the said weight of such units and the relatively insecure mounting of said stub portions on said posts, and whereby said stub portions may be individually or collectively replaced when their respective card portions have been detached.

GUSTAVE A. WILKE.
